UNITED STATES PATENT OFFICE.

HORATIO N. LAND AND HOWARD CAMPBELL, OF RICHMOND, INDIANA, AS-SIGNORS TO GAAR, SCOTT & COMPANY, OF SAME PLACE.

CYLINDER FOR CLOVER-HULLERS.

SPECIFICATION forming part of Letters Patent No. 295,771, dated March 25, 1884.

Application filed January 7, 1884. (No model.)

To all whom it may concern:

Be it known that we, HORATIO N. LAND and HOWARD CAMPBELL, citizens of the United States, residing at Richmond, in the county of 5 Wayne and State of Indiana, have invented new and useful Improvements in Cylinders for Clover-Hullers, of which the following is a specification.

This invention has for its object to provide 10 a clover-hulling cylinder which will readily and efficiently remove the seed from the pods, and which possesses the advantages of a solid and practically continuous rubbing or hulling surface, and of an open or hollow cylinder for 15 conveniently attaching and adjusting the rubber-teeth or replacing a broken or injured rubber-tooth by a new one. This is accomplished by the novel construction and combination of devices comprising the cylinder, which are 20 hereinafter described and claimed, reference being had to the accompanying drawings, in which—

Figure 1 is a perspective view of a hulling-cylinder made in accordance with the invention, one of the corrugated or roughened rubbing-plates being detached; Fig. 2, a detached perspective view of one of the corrugated or roughened rubbing-plates, and Fig. 3 a perspective view of one of the projecting rubbers 30 of ordinary construction.

In clover-hulling cylinders where wood is used, it is subject to swelling and shrinking, thus throwing the cylinder out of proper balance, and by swelling produce an uneven surface or periphery which tends to crack or mash the seed, while the parts become loose, all of 35 which is objectionable, and to avoid this we construct all the parts of metal. The metal cylinder-heads number 1 are centrally mounted 40 on a supporting-shaft, 2, and around the periphery of each is provided a series of properly-spaced recesses, 3, in which are arranged the extremities of the metal lags 4, said lags being confined in the recesses by annular bands 45 or flanges 5, properly secured to the cylinder-heads and overlying the extremities of the lags. An annular band, 6, also encircles the lags at or near the middle of their length, while the inner sides of the cylinder-heads, at a short 50 distance from their peripheries, are cast or

otherwise provided with projecting lugs or ears 8, also having screw-holes. The spaces between the lags are occupied by the corrugated or roughened rubbing-plates 9, which are curved to correspond to the circle which the cylinder 55 is to describe. The ends of these rubbing-plates are provided with projecting bearings 10, through which and the plate extend openings for the passage of set screws or bolts 11, for attaching the plates to the lugs or ears, the 60 said bearings 10 resting on the lugs or ears and supporting the roughened or corrugated surfaces of the plates in proper position to perform their function of rubbing out the seed from the clover-pods. The lags 4 are perforated at proper intervals along their length for receiving the screw-threaded shanks 12 of the usual projecting metallic rubber-teeth, 13, and to the threaded shanks are applied nuts 14 for clamping and holding the rubber-teeth in position on the lags. The corrugated or roughened 65 plates provide an efficient rubbing-surface longitudinally between the lags, while by unscrewing the set-screws 11 and detaching one or more of the said plates access can be conveniently had to the interior of the cylinder for the purpose of attaching and adjusting the rubber-teeth 13, or for replacing a broken or injured rubbing-tooth, while if one of the corrugated or roughened rubbing-plates becomes 70 broken or injured it can be readily removed and replaced by another. The lugs or ears cast or otherwise attached to the inner sides of the cylinder-heads provide simple and efficient means for the attachment of the outer 75 ends of the rubbing-plates through the medium of simple set screws or bolts, and in order that the heads of such screws or bolts may not project unduly outward, we provide countersinks 80 around the openings through which the 85 screws pass, so that the heads of the screws can enter the countersinks and lie below or flush with the acting surface of the plates. The central band and its lugs or ears are not absolutely essential, and may be omitted, in 90 which case, however, the rubbing-plates will each be made of such length as to extend from the lug or ear of one cylinder-head to the lug or ear on the other; but we prefer the construction shown, as providing a firm and rigid 95 100

support for the parts midway the length of the cylinder.

By the means described, we provide a practically continuous corrugated or roughened rubbing-surface to the periphery of the cylinder, which is very advantageous in rapidly rubbing the seed from the pods, while the construction of parts is such that the rubbing-plates extend longitudinally between the lags and can be quickly removed and replaced.

We have not considered it necessary to illustrate the concave in which the cylinder revolves, as such may be of any usual construction—such, for example, as wooden bars filled 15 with rubber-teeth like those on the cylinder.

Having thus described our invention, what we claim is—

1. The combination, in a clover-hulling cylinder, of the cylinder-heads having lugs on their 20 inner sides, the longitudinal lags, the detachable rubber-teeth thereon, the rubbing-plates extending longitudinally between the lags and detachably connected to the lugs, substantially as described.

2. The combination, in a clover-hulling cylinder, of the cylinder-heads having lugs on their inner sides, the longitudinal lags, the rubber-teeth having shanks projecting through the lags, the nuts holding the rubber-teeth, and the rubbing-plates extending longitudinally between the lags and detachably connected to the lugs, substantially as described. 25

3. The combination of the cylinder-heads, having lugs on their inner sides, the lags, the rubber-teeth detachably secured in the 30 lags, the rubber-plates extending longitudinally between the lags, and the screws connecting the plates to the lugs, substantially as described. 35

In testimony whereof we have hereunto set 40 our hands in the presence of two subscribing witnesses.

HORATIO N. LAND.
HOWARD CAMPBELL.
